(57) **CLAIM**

The ornamental design for an insect trap, as shown and described.

DESCRIPTION

FIG. 1 is a front and top perspective view of an insect trap, showing my new design;

FIG. 2 is an exploded view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines showing of portions of the insect trap is included for purpose of illustrating only and form no part of the claimed design.
